(57) **CLAIM**

The ornamental design for a guitar bridge protection plate, as shown and described.

DESCRIPTION

FIG. 1 is an elevation view of the guitar bridge protection plate showing my new design;

FIG. 2 is a top view of the guitar bridge protection plate of FIG. 1;

FIG. 3 is a bottom view of the guitar bridge protection plate of FIG. 1; and,

FIG. 4 is a side view of the guitar bridge protection plate of FIG. 1.

The details shown in broken lines form no part of the claimed design.
